(57) **CLAIM**

The ornamental design for a display screen with icon, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen with icon; and, FIG. 2 is a second embodiment thereof.

The broken line showing the display screen illustrates portions of the article and forms no part of the claimed design.
